UNITED STATES PATENT OFFICE.

HERMAN T. SUNDSTROM, OF HOUSTON, TEXAS, ASSIGNOR TO MERGENTHALER LINOTYPE COMPANY, A CORPORATION OF NEW YORK.

SAFETY ATTACHMENT FOR LINOTYPES AND INTERTYPES.

Application filed September 5, 1922. Serial No. 586,314.

To all whom it may concern:

Be it known that I, HERMAN T. SUNDSTROM, citizen of the United States, residing at Houston, in the county of Harris and State of Texas, have invented certain new and useful Improvements in Safety Attachments for Linotypes and Intertypes, of which the following is a specification.

This invention relates to new and useful improvements in a safety attachment for linotypes and intertypes.

The object of the invention is to provide an attachment of the character described which will operate automatically to stop the matrices before they reach the intermediate channel of the linotype, in case they have been improperly assembled in the assembling elevator.

In operating a linotype, the matrices are first assembled in the assembling elevator by means of which they are elevated into alignment with the intermediate channel through which they are sent on their way to the mold disc. Some of these matrices are capable of being assembled in two positions, that is, in upper or in lower position. If the matrices are smaller than fourteen point, they may be assembled in lower or upper position so as to align perfectly with the mold disc when carried into position for casting. If over fourteen points they must be assembled in lower position, or they will not align with said disc, and casting material will not be projected directly against said matrices, and an imperfect casting will result; and furthermore the molten material will escape, causing what is known as "front overflow" or "front squirt."

It is the object of this invention to provide an attachment of the character described which will automatically stop the matrices before they reach the intermediate channel, in case they have been assembled in the wrong position in the assembling elevator, and when the matrices have been so stopped, they can be then adjusted to the lower position before they are sent on through the intermediate channel to the molding disc of the linotype.

With the above and other objects in view, the invention has particular relation to certain novel features of construction, operation and arrangement of parts, an example of which is given in this specification and

illustrated in the accompanying drawings, 55 wherein:—

Figure 1 shows a side elevation of the vise cap, of a linotype, showing an assembling elevator and intermediate channel associated therewith, and 60

Figure 2 is an enlarged fragmentary view, 65 of the safety attachment.

Referring now more particularly to the drawings wherein like numerals of reference designate similar parts in each of the figures, the numeral 1 indicates the first elevator filling piece which is hinged to the top of the vise cap 2, by means of the hinge 3. The matrices 4 are composed in an assembler or assembling elevator 5, and from 70 this elevator they travel along the intermediate channel 6, on their way to the mold disc. In case matrices larger than fourteen points are assembled in the upper position, in the assembling elevator, they will not 75 align with the mold disc, provided for them and consequently, should be adjusted before they reach said disc, to lower position, so as to come into perfect alignment therewith. To permit said adjustment, said 80 matrices must be stopped before they reach the intermediate channel 6, and the attachment for stopping them for this adjustment will now be described:

A bar 7 is provided, one end of which is 85 pivoted at the point 8 and the other end of which has a limited vertical movement. This last mentioned end is aligned over the line of matrices in the assembling elevator. The pivoted end of the bar has a depending 90 integral arm 9 provided to interlock with one arm of the bell crank 10 which is pivoted to the frame of the channel 6. An actuating rod 11 is mounted upon the vise cap 2 and is slidable lengthwise in the bearing 12. 95 The filling piece 1 has a laterally extending pin 13 projecting therefrom near its hinged end and the adjacent end of the rod 11 is bent upwardly at right angles forming the stud 14 against which the pin 13 rests when 100 the filling piece 1 is in active position. The opposite end of the rod 11 carries the bearing plate 15 which operates against the free end of the other arm of the bell crank 10.

When said filling piece 1 is in active position on the vise cap, as shown in Figure 1, the pin 13 operates against the stud 14 to 105 actuate the rod 11 and force the plate 15

against the adjacent arm of the bell crank 10 and this operates to carry the other end of said bell crank into locking engagement with the arm 9. The bar 7 is thereby held locked against movement and should some of the matrices be improperly assembled in elevated position, as indicated in Figure 1, when the assembling elevator is elevated they will contact against said bar and be stopped before they are fully elevated into alignment with the intermediate channel 6, and consequently will not be able to pass along said channel to the mold disc, until they have been lowered into lower position. The stop of the matrices will attract the operator's attention so that he will not overlook adjusting the same to proper position before they have entered the intermediate channel. In case matrices of fourteen point or less are being assembled the filling piece 1 is thrown into inactive position, as shown in full lines in Figure 2, carrying the pin 13 out of contact with the stud 14 and releasing the bell crank 10 by the pull of a coil spring 16, one end of which is attached to said bell crank and the other end of which is attached to the frame of the intermediate channel. The pull of this spring operates to release the bell crank from locking engagement with the arm 9, thereby unlocking the bar 7 and permitting the elevation thereof so that it will not interfere with the passage of said matrices, it being immaterial whether or not said last mentioned matrices are assembled in upper or lower position, as in either case they will align with the mold disc provided for them. As is well understood in the art, the assembling elevator 5, when elevated into registration with the intermediate channel 6, trips a transfer carriage which shifts the composed line out of the elevator and through the intermediate channel into a so-called first elevator whereby the line is presented to the mold for the slug casting operation, the vertical position or level of the first elevator with reference to the mold being determined by the filling piece 1 before mentioned. It is evident, therefore, that when the assembling elevator is arrested in its upward movement by the locking bar 7, it fails to trip the transfer carriage and hence allows the composed line to remain in the elevator. As a matter of fact, however, the same effect would follow even if the transfer carriage were tripped, due to the lack of registration of the assembling elevator and the intermediate channel. The transfer carriage and the first elevator, together with all other parts of the machine not herein shown, are so well known that it has not been deemed necessary to illustrate them herein. For the same reason, it has been thought unnecessary to enlarge upon

the description of the known parts herein illustrated.

What I claim is:

1. In a device of the character described, the combination with a channel along which matrices travel to the molding disc of an assembling elevator provided to carry said matrices into alignment with said channel, a locking mechanism adapted to contact against the matrices while in said elevator, and stop them before they enter said channel, and a first elevator filling piece which, when in active position, operates to hold said mechanism in locked position. 75

2. In a device of the character described, the combination with an intermediate channel, forming a track for the passage of matrices, of an assembling elevator provided to receive said matrices, and elevate them into alignment with said channel, a stop bar which aligns with said matrices to arrest the upward movement of the assembling elevator, a first elevator filling piece, a mechanism actuated by the filling piece when moved to active position, and connected to said bar to hold the same locked against said matrices, said filling piece releasing said mechanism when moved to inactive position to permit the release of said bar from said matrices. 85 95

3. In a device of the character described, the combination with an intermediate channel, forming a track for the passage of matrices, of an assembling elevator provided to receive said matrices and elevate them into alignment with said channel, a stop bar which aligns with said matrices and formed at one end with a depending arm, a bell crank, a filling piece, an actuating rod arranged to be actuated by said filling piece, 105 when in active position, to manipulate said bell crank into locking engagement with said arm whereby said bar is held locked against the matrices, said filling piece releasing said rod when moved to inactive 110 position to permit the release of said bell crank from said arm, and means for releasing the bell crank from said arm. 115

4. In a typographical composing and casting machine, the combination of an assembler wherein the matrices are composed in an upper or lower position as desired, an adjustable device to determine the level at which the composed matrices are presented to the mold, and automatic means to prevent or permit the shifting of the composed matrices out of the assembler according to the adjustment of said level determining device and the position of the matrices in the assembler. 120

5. In a typographical composing and casting machine, the combination of a vertically movable assembler wherein the matrices are composed in an upper or lower position as desired, an adjustable device to determine 125 130

the level at which the composed matrices are presented to the mold, and automatic means to prevent or permit the full upward movement of the assembler according to the adjustment of said level determining device and the position of the matrices in the assembler.

6. In a typographical composing and casting machine, the combination of an assembler wherein the matrices are composed in an upper or lower position as desired, an adjustable device to determine the level at which the composed matrices are presented to the mold, and a safety means controlled by said adjustable device to permit or prevent the shifting of the composed matrices out of the assembler while occupying an upper position therein.

7. In a typographical composing and casting machine, the combination of a vertically movable assembler wherein the matrices are composed in an upper or lower position as desired, an adjustable device to determine the level at which the composed matrices are presented to the mold, and a safety means controlled by said adjustable device to prevent or permit the full upward movement of the assembler while matrices are occupying an upper position therein.

8. In a typographical composing and casting machine, the combination of a vertically movable assembler wherein the matrices are composed in an upper or lower position as desired, an adjustable device to determine the level at which the composed matrices are presented to the mold, a movable member arranged to be engaged by matrices standing in an upper position in the assembler during the upward movement of the latter, and means to prevent or permit the movement of said member according to the adjustment of the level determining device.

9. In a typographical composing and cast-

ing machine, the combination of a vertically movable assembler wherein the matrices are composed in an upper or lower position as desired, a filling piece adjustable to active or inactive position to determine the level at which the composed matrices are presented to the mold, a movable member arranged to be engaged by matrices standing in an upper position in the assembler during the upward movement of the latter, and means for locking said member against movement when the filling piece is in active position.

10. In a typographical composing and casting machine, the combination of a vertically movable assembler wherein the matrices are composed in an upper or lower position as desired, a filling piece adjustable to active or inactive position to determine the level at which the composed matrices are presented to the mold, and means operative in the active position of the filling piece to prevent the full upward movement of the elevator while matrices are standing in an upper position therein.

11. In a typographical composing and casting machine, the combination of an assembler wherein the matrices are composed in an upper or lower position as desired, a filling piece adjustable to active or inactive position to determine the level at which the composed matrices are presented to the mold, and means operative in the active position of the filling piece to prevent the shifting of the composed matrices out of the assembler while matrices are standing in an upper position therein, said means permitting the matrices to be composed in the assembler in said upper position.

In testimony whereof I have signed my name to this specification.

HERMAN T. SUNDSTROM.
